UNITED STATES PATENT OFFICE.

SAMUEL G. BARGERY, OF DETROIT, MICHIGAN.

INTERNAL-COMBUSTION ENGINE.

1,197,591.

Specification of Letters Patent. Patented Sept. 12, 1916.

Application filed September 30, 1915. Serial No. 53,438.

To all whom it may concern:

Be it known that I, SAMUEL G. BARGERY, a subject of the King of Great Britain and Ireland, residing at Detroit, in the county of Wayne and State of Michigan, have invented certain new and useful Improvements in Internal-Combustion Engines, of which the following is a specification, reference being had therein to the accompanying drawing.

10 The invention relates to having a reciprocating piston and a rotating member therewithin, being more particularly designed for use as an internal combustion engine, but also operable by other motive fluids.

15 The invention comprises various features of construction as hereinafter set forth.

In the drawings: Figure 1 is a central longitudinal section through the engine; and Fig. 2 is a cross section thereof.

20 A is a casing having opposite aligned cylindrical portions B and C connected by an intermediate portion D.

E is a hollow piston bridging the intermediate portion D and engaging and reciprocating in the opposite cylinders B and C.

25 F is a rotary cam within the piston E, which is mounted upon a shaft G extending outward through one end of said piston and cylinder and providing sufficient clearance for the free reciprocation of the piston.

To convert the reciprocatory movement of the piston into rotary movement of the cam F, the latter is provided with a cycloidal endless groove H which is engaged at di-

30 ametrically opposite points by roller bearings I and I' mounted on the piston. The piston is also provided with external roller bearings J which engage longitudinal grooved guides K formed in the intermediate portion D of the casing, the arrangement being such that the piston is compelled to travel in a rectilinear path by the guides K, while the engagement of the rollers I with the groove H will communicate a rotary 35 movement to the cam F.

The rolls I and J are preferably connected to a common pivot member L which passes through a removable bearing M engaging a threaded aperture in the walls of 40 the piston E. The piston is provided with rings N or other means of forming a tight connection with the cylinders B and C, and a ring or packing O engaging a sleeve bearing P in which the shaft G is journaled. Endwise movement of the shaft G and cam member F is prevented by suitable thrust

bearings, and as shown one of these is formed by the cam and the other by a collar Q on the shaft G.

With the construction as thus far described, it is evident that the alternate introduction and exhaustion of a suitable motive fluid in the cylinders B and C will impart reciprocating movement to the piston, which through the mechanism described will convert this movement into rotary movement of the cam F and shaft G. Preferably the motive power is developed by internal combustion, and as shown the engine is organized as a two-cycle gas engine. The explosive charge is introduced through an inlet valve R into the cylinder C during the outward stroke of the piston and is compressed upon the return stroke, until a transfer port S leading from the cylinder C 65 to the cylinder B is opened by the movement of the piston in the latter cylinder. This will admit the compressed gaseous charge to the cylinder B, where it will expel the products of a previous explosion 70 through an exhaust port T, as is usual in two-cycle engines. The cylinder B is preferably water-jacketed as indicated at U, and a spark-plug V is provided for ignition.

In order to equalize the volumes of the two cylinders B and C and to expose equal piston areas therein the cylinder C is of slightly greater diameter than the cylinder B, so as to compensate for the cross section of the shaft G and sleeve bearing P.

90 What I claim as my invention is:—

1. In an engine, the combination with a casing having axially-aligned opposed cylindrical portions and an intermediate portion of greater diameter than said cylindrical portions having longitudinally-extending guides, of a hollow piston bridging said intermediate portion and reciprocating in said cylindrical portions, a rotary cam within said hollow piston, a shaft on which said cam is mounted extending out through one end of said piston and cylinder, thrust bearings for holding said shaft from endwise movement, and means mounted on said piston coöperating with said rotary cam and said longitudinal guides for converting the reciprocatory motion of the piston into rotary motion of the cam.

2. In an engine, the combination with a casing having axially-aligned opposed cylinder portions and an intermediate connecting portion providing longitudinal guides,

- of a hollow piston bridging said intermediate portion and reciprocatingly engaging said cylinder portions, a rotary cam within said hollow cylinder, a shaft on which said cam is mounted passing outward axially of said piston and cylinder, a thrust bearing for preventing endwise movement of said cam and shaft, and diametrically opposed members upon said hollow piston extending inward and outward therefrom respectively engaging said cam and said longitudinal guides to convert the reciprocatory motion of the piston into rotary movement of the cam.
- 15 3. An engine, comprising a casing having opposed axially-aligned cylinder portions and an intermediate portion providing longitudinally-extending guides, a hollow piston bridging said intermediate portion and reciprocatingly engaging said cylinder portions, a rotary cam within said hollow cylinder, a shaft on which said rotary cam is mounted passing axially out through said piston and cylinder, means for preventing endwise movement of said cam, bearings on said piston member respectively engaging said rotary cam and longitudinal guides, and means for introducing a gaseous charge in one of said cylinders and for transferring said charge, compressing and exploding the same in the opposite cylinder.
- 5 4. An engine, comprising a casing having axially-aligned opposed cylinder portions and an intermediate connecting portion providing longitudinally-extending guides, a hollow piston bridging said intermediate portion and reciprocatingly engaging said cylinder portions, said intermediate portion being spaced from said piston, a rotary cam within said hollow piston, a shaft on which said cam is mounted passing axially out through said piston and cylinder, means mounted on said piston coöperating with said guides and cam for converting the reciprocatory movement of said piston into rotary movement of said cam and shaft, and means for utilizing said opposite cylinder portions for the compression and explosion of a gaseous charge to reciprocate said piston.
